UNITED STATES PATENT OFFICE.

PHILIP F. KRUG, OF NEW YORK, N. Y.

MOVING-PICTURE MACHINE.

1,183,082.

Specification of Letters Patent. Patented May 16, 1916.

Application filed September 26, 1913. Serial No. 792,013.

To all whom it may concern:

Be it known that I, PHILIP F. KRUG, a citizen of the United States, and a resident of the city of New York, borough of Brooklyn, county of Kings, and State of New York, have invented certain new and useful Improvements in Moving-Picture Machines, of which the following is a specification.

My invention relates to a moving picture machine and one of the objects of the invention is to provide an improved and a simplified mechanism to intermittently and positively and silently work the picture film across the picture aperture or optic axis of the machine. Accordingly, I provide, in connection with the usual constantly moving film take-up mechanism, an engagement to bear intermittently on a loop formed in the film after it has been fed past the aperture and to quickly jerk the succeeding picture units into framed position in the aperture after which the spent film is worked on to the take-up reel by a take-up sprocket as is usual with devices of this character.

Another object of the invention is to provide a simple and quickly actuated means for accurately framing the picture units without interrupting the actuation of the machine, without affecting the film driving mechanism and without moving any holding frame or other material part of the machine.

A further object of the invention is to provide a simple means for adjusting the ratio between the time intervals during which the picture unit is held stationary and during which the next unit is being moved into its held position.

Various other objects and advantages will be in part obvious and in part more fully set forth in the following description of a preferred embodiment of my invention which also includes certain new and novel features of construction and combination of parts hereinafter set forth and claimed.

In the drawings:—Figure 1 is a fragmentary side elevation of a portion of a moving picture machine head showing a preferred embodiment of my invention installed therein. Fig. 2 is a front elevation of the lower portion of the device shown in Fig. 3. Fig. 3 is an enlarged detail view of a portion of the cam movement shown in Fig. 1, and Fig. 4 is an enlarged sectional view on the line 4—4 of Fig. 1.

There is shown a frame 1 forming a part

of the head of a moving picture machine having the usual aperture 2 across the optic axis of the machine and having the usual feed sprocket 3 and take-up sprocket 4, the latter suitably geared together and driven continuously and in unison from a shaft 5 which may be the main drive shaft.

A pivot pin 6 is carried by the frame, which pin extends parallel to the plane of the film and has suspended therefrom, the upper end of a rocking arm 7, the lower end of which is formed into a disk 8 disposed between an extension 9 of the frame 1 and a hand lever 10 which projects forwardly of the machine convenient to the operator. A transversely extending bolt 11 passes through said extension, disk and lever to fasten these members together, and preferably is drawn into a frictional tight engagement therewith so that the parts will remain in their shifted positions. The lever 10 carries a pin 12 which extends into a slot 13 in the disk 8 which slot is disposed in substantially radial position relative to the axis of the bolt 11, which is disposed in a slot 25 in the disk 8.

A lever 15 is fulcrumed adjacent one end of the pivot pin 16 which parallels the pin 6 and has its other end suitably journaled in a wide portion of the arm 7 intermediate its length. A pair of horizontally spaced rollers 17 and 18 are rotatably mounted on the lever 15 and on opposite sides of the pin 16.

To give the rollers a reciprocating movement, an extension 19 from the lever 15 is connected by a link 20 with the eccentric pinion 21 which is mounted on the frame and is in mesh with the gear wheel 22 driven from the driving shaft 5.

The picture film 23 is fed by the sprocket 3 into an upper loop 24, from which it is drawn into its usual frictional engagement with the picture aperture 2. From the picture aperture it passes in an S shaped loop about opposite sides of the rollers 17 and 18 in succession and passes on to the usual take-up sprocket 4 to the usual take-up reel, not shown. By means of this device the rollers 17 and 18 reciprocate in opposite directions about the fulcrum pin 16 to intermittently form a pronounced S shaped loop in the film and then disengage themselves from the loop permitting the sprocket 4 to partially take up the loop and on the next engagement of the rollers with the film an-

other portion of the film is drawn across the aperture. The sprocket 4 is continually feeding the film; during the periods when the film is stationary in the aperture, the sprocket is taking up the lower S shaped loop and during the movement of the film across the aperture the sprocket is assisting to draw the film about the rollers 17 and 18 thus permitting a very rapid intermittent movement of the film.

Should it be necessary to frame the picture units the handle of the lever 10 may be raised or lowered, which acts through the pin 12 to bear on the lever 7 swinging the same on its pivoting arm 6, thus bringing the mean position of the rollers closer to or further from the picture aperture and due to the particular form of connection between the lever and arm 7, the movement 20 of the lever is much reduced so that a refined adjustment of the position of the units relative to the horizontal edges of the aperture is attained.

Further the framing of the picture by this means does not necessitate any shifting of the main film driving mechanism as the sprockets 3 and 4 are securely mounted in fixed position in the machine and positively connected to the main driving shaft 5. It is merely necessary to shift slightly the position of the arm 7 and this shifting in no way affects the actuation of the intermittent feeding mechanism carried thereby.

It is noted that the rollers 17 and 18 have plain peripheries and engage the film entirely on one side and for some material distance along the length thereof, thereby minimizing the danger of ripping the side apertures in the film as it is fed through the machine. Further these rollers are inexpensive and even wooden spools have been found to be very effective. There is thus eliminated the expensive milled parts at present constituting the Geneva stop feed and the equally objectionable engagement of a toothed member with the apertures in the film as this intermittent movement places a severe strain on the film about the side apertures. With devices of this character it has been observed that the rollers in their rapid movement into engagement with the film forms minute cracks transversely of the same and these cracks become more pronounced as the film was repeatedly used. It was found experimentally that the film should be engaged by a flat surface or rather a slightly curved surface to eliminate this cracking action and as this ideal contacting surface was not possible, the rollers are made with as large a diameter as possible so as to present a periphery with the least possible curvature and the parts are so arranged that the film engages almost half of the periphery. To identify the size of these rollers it may be said that they should have a diam-

eter not less than the width of the film to avoid destroying the film after it has been used a few times.

By means of this construction the ratio of periods of rest to periods of motion of the film at the aperture may be readily varied by moving the pivotal connection of the link 20 with the extension 19 toward or from the pivotal pin 16.

As the object of the intermittent feed is primarily to draw the film across the aperture, it is obvious that the roller 18 may revolve about a fixed axis, in which case the roller is mounted on the frame, and the roller 17 alone reciprocated back and forth to alternately form a single loop in the film instead of the double or S shaped loop hereinbefore described, and to make up for the limited movement, the roller may be spaced from the center of oscillation 16 of the lever 15.

The parts disclosed are simple in construction and assemblage, may be readily dismounted for repairs and substitution of parts and minimize strains on the picture film.

Although I have shown one form of mechanism embodying my invention, it is obvious that various changes within the skill of the mechanic may be made therein without departing from the spirit of the invention, provided the means set forth in the following claims are employed.

Having thus described my invention, I claim:

1. In a moving picture machine, the combination with a frame, a depending arm having its upper end pivoted to the frame, a reciprocating film feeding mechanism mounted on said arm, a lever engaging the lower end of the arm for adjusting the position of said arm relative to said frame, a film driving shaft revolvably mounted in fixed position in the frame, and means continuously reciprocating said mechanism from the rotary movement of said shaft.

2. In a device of the class described, a support, a broad plate having one end pivoted to said support, a shaft journaled in said plate and projecting therefrom, a lever having a plurality of arms pivoted to the projecting portion of said shaft, a film actuating roller carried by one arm of said lever, a reciprocating link pivoted to the other arm of said lever, means for reciprocating said link and manually actuated means including a pin and slot connection engaging the end of said plate opposite the pivoted end for swinging the same about its pivotal connection thereby to adjust the position of said roller.

3. In a moving picture machine, means for feeding the film intermittently across the picture aperture comprising a lever pivoted intermediate its length, a pair of film

engaging rollers rotatably mounted on opposite sides of the pivotal connection of the lever, said rollers having their axes of rotation parallel to each other and to the plane of the film adapted to have the film looped 5 **S** shape about the same, said lever having an extension therefrom, means engaging said extension for reciprocating the lever in all positions of the same whereby said lever with its rollers is rocked to feed the film and means operatively connected to said lever to vary the position of the pivotal 10 point of the same thereby to frame the film.

4. In a moving picture machine, means 15 for feeding the film intermittently across the picture aperture comprising a pivoted lever, a film engaging roller rotatably mounted on said lever and spaced from the pivotal connection of the lever, an extension

from said lever, said extension having a plurality of link engaging means spaced unequally from the pivotal connection of the lever, a rotary member having a fixed axis of rotation, a link having one end pivoted to said rotary member at a point offset from 25 its axis of rotation and having the other end pivotally connected to one of the engaging means on the extension, said other end adapted to be shifted to another of said engaging means thereby to vary the extent of 30 movement of the roller.

In witness whereof I have hereunto set my hand in the presence of two witnesses.

PHILIP F. KRUG.
